To resemble, when suspended, a light weight receptacle, and to facilitate the removal of refuse and the disposal of refuse in a refuse receptacle suspended from a vertical pole or other support.

UNITED STATES PATENT OFFICE

Subject matter claimed in this patent is set forth in the claims which follow. This invention relates to a waste receptacle, and particularly to a suspended waste receptacle.

WASTE RECEPTACLE

Applicant, Sidney F. Croft, Jr., Charlotte, N. C., assignor to Sydell Manufacturing, Incorporated, a corporation of North Carolina.

Application October 2, 1950, Serial No. 187,999

2 Claims. (Cl. 232—43.1)

1. This invention relates to waste receptacles and more particularly to suspended waste receptacles adapted for receiving refuse and waste through openings in their upper portion and being emptied from openings in their lower portion.

The common types of waste receptacles in present use either in private homes or in public places are heavy, round or rectangular shaped metal containers which rest on the ground and which are filled and emptied through tops having removable covers. As is well known, the emptying of these containers and their maintenance in a sanitary condition involve difficulties of which civic minded citizens are acutely aware. Furthermore, prior efforts to alleviate these difficulties by suspending waste containers adapted for being emptied from the bottom have been unsuccessful since the emptying arrangements interfered with the garbage or waste collector and the containers were not suitable for the heavy duty requirements of constant use.

The suspended waste receptacle of the present invention overcomes these disadvantages by providing a container which is easily emptied by the municipal collectors of garbage and refuse, which is capable of being cleaned easily by the householder, the apartment dweller or the city maintenance department, and which, as a matter of economy in both manufacture and use, requires a lighter weight material and is longer lasting in use.

According to the present invention these advantages are afforded by the unique arrangement of a waste receptacle having openings in its upper and lower portions, hinged doors covering these openings, a fixed bottom sloping downwardly to and communicating with a lower opening, means for locking the lower door to the bottom, and means for suspending the waste receptacle in fixed relation to a surface.

The waste receptacle of the present invention is described in further detail below in connection with the accompanying drawings, in which:

Figure 1 is a perspective view of a waste receptacle constructed in accordance with the present invention suspended on a white way pole;

Figure 2 is a perspective view corresponding generally with Figure 1, showing the door to the lower opening in open position to expose the fixed, sloping bottom;

Figure 3 is a section taken substantially on the line 3—3 in Figure 2;

Figure 4 is a section taken substantially on the line 4—4 in Figure 3;

Figure 5 is a perspective view of the locking

means adapted to be attached to the lower door and to the bottom;

Figure 6 is a front elevation of a modification of the present invention in which the upper opening and door therefor are positioned in the slanting top of the waste receptacle;

Figure 7 is a top plan view, partly broken away, of the modified waste receptacle shown in Figure 6; and,

10 Figure 8 is a side elevation corresponding generally with Figure 6, showing the suspension of the receptacle on a flat surface.

Referring now to the drawings in detail, and more particularly at first to Figures 1 and 2, the waste receptacle of the present invention, as shown, comprises an enclosed box-like structure having side walls 10, a front wall 12, a back wall 14, a top 16, and a fixed bottom member 18.

The front wall 12 is provided with an opening 20 in its upper portion, and a door 22 hinged at 24 for covering the opening 20. The front wall 12 and side walls 10 are cut away at 26 to form an opening 28 in the front lower part of the waste receptacle. A door 30 is hinged to the front wall 12 at 32 to cover the lower opening 28, and the fixed bottom member 18 slopes downwardly to and communicates with lower opening 28.

As shown in Figures 3 and 4, the back wall 14 is formed with a vertically extending concave channel 34 which is disposed intermediate of the side walls 10. This concave channel 34 adapts the waste receptacle of the present invention for suspension to a white way pole 36 by use of suitable attaching means such as metal clamps 38 which are affixed around the white way pole 36 and attached to the back wall 14 by bolts and nuts 40 and 42, respectively.

As shown in Figures 3 and 4, the door 22 covering the upper opening 20 is conveniently arranged to swing inwardly of the receptacle and has a weight 44 arranged on its downwardly extending edge 46 to maintain the door 22 in a closed position when not in use.

45 As shown in Figures 2 and 5, the door 30 for the lower opening 28 and the fixed bottom 18 are provided with suitable locking means, indicated generally by the reference numeral 46. The door 30 is formed at its extending end with a curved portion 48 for gripping snugly in closed position a corresponding curved portion 50 provided in the downwardly extending edge 52 of the bottom 18.

As shown clearly in Figure 5, the locking means 46 comprises a U-shaped hook 54 fixedly arranged 55 on the curved end portion 48 of the door 30, and

a tongue 56 pivotally arranged to a bracket 58 which is fixedly attached to the underside of the bottom 18 at 60, and a latch 62 pivotally arranged on flanges 64 formed integrally with the tongue 56. In locked position, as illustrated in Figure 4, the door 39 is held in a closed position and in interlocking relation with the fixed bottom member 18.

In Figures 6, 7 and 8, a modification of the waste receptacle of the present invention is shown and comprises essentially the same features described above. As shown, a door 66 is hinged at 68 adjacent the back wall 14' to cover an opening 70 in the slanting top 16', and this door 66 is provided with a conventional handle 72 in its rounded extended end 74.

The rear wall 14', as shown in Figures 7 and 8, is flat and the waste receptacle is attached to a flat surface by suitable bolts 76 which are disposed in the upper portion of the back wall 14' and at 78 below the point where the bottom 18 joins the back wall 14'.

By these arrangements, the waste receptacle of the present invention provides a useful, economically constructed, easily cleaned device for receiving refuse and waste either on the city streets when suspended on white way poles, as shown in Figures 1 to 4 inclusive, or on the walls of homes or garages for the individual householder or the apartment dweller, as shown in Figures 6 to 8 inclusive. The device of the present invention may be used to particular advantage for these purposes because it allows the receptacle to be suspended out of the way either on poles or on walls, permits the receptacle to be made of lighter weight metal or like material, as contrasted with the common type of heavy metal receptacle which rests on the ground, and lessens the work of the garbage and trash collector in view of the elimination of the manual handling of the receptacle. The sloping bottom 18 of the present invention has a fourfold advantage, namely, it facilitates the removal of the trash in that the waste and refuse will tend to drop from this sloping surface, its fixed arrangement does not interfere with the can or container of the collector which is positioned below the opening 28 when the waste receptacle of the present invention is being emptied, it presents an easily accessible surface for cleaning by the sanitation department of the city or by the householder or apartment dweller, and finally it enables positioning of the attaching means below the interior of the waste receptacle, and this disposition of the attaching means prevents the rusting out or corrosion of bolts or the like used to attach the receptacle to a surface which would be true if waste and refuse were constantly in contact therewith.

It will be understood that the applicant is not limited to any particular shape of enclosed structure, to any specific type of door for the openings 20 and 28, to any particular material from which

the waste receptacle might be made, whether of metal, pressed fiber or the like, to any specific means by which the waste receptacle is attached to a surface, or any particular means by which the lower door 30 is locked to the bottom 18, as shown and described herein above.

I claim:

1. In an enclosed, suspended receptacle having an opening in its upper portion for receiving waste, an opening in its lower portion for emptying said waste, and a fixed bottom member sloping downwardly to and communicating with said lower opening, the improvement which comprises side members of said receptacle being cut away adjacent said lower opening so that the fixed bottom member extends beyond the cut away edges of said side members, and a door hingedly connected to the front of said receptacle at the upper edge of said lower opening and formed with a curved lower flange and side flanges for covering relation with the downwardly extending edge of said fixed bottom member and with the cut away edges of said side members respectively.

2. In an enclosed, suspended receptacle having an opening in its upper portion for receiving waste, an opening in its lower portion for emptying said waste, and a fixed bottom member sloping downwardly to and communicating with said lower opening, the improvement which comprises side members of said receptacle being cut away adjacent said lower opening so that the fixed bottom member extends beyond the cut away edges of said side members, a door hingedly connected to the front of said receptacle at the upper edge of said lower opening and formed with a curved lower flange and side flanges for covering relation with the downwardly extending edge of said bottom member and with the cut away edges of said side members respectively, and a pivotally arranged latch and a hook disposed on said curved lower flange and on the underside of said fixed bottom member to engage and extend in latched position rearwardly from the extending edge of said bottom member and beneath the bottom of said receptacle.
